His Attorney.

UNITED STATES PATENT OFFICE.

ARTHUR C. GLASGOW, OF DECATUR, ILLINOIS.

COAL-FEEDING MECHANISM.

Application filed February 16, 1920. Serial No. 359,207.

To all whom it may concern:

Be it known that I, ARTHUR C. GLASGOW, a citizen of the United States, and residing at Decatur, Illinois, have invented the new and useful Improvement in Coal-Feeding Mechanism, of which the following is a specification.

This invention relates to an apparatus for feeding pulverized fuel and similar materials.

In an apparatus of this kind, the material is usually delivered to the feeding device by means of a hopper. It is a peculiarity of pulverized material that, after having been stored, even for a short period of time in a bin or hopper from which it is fed by withdrawing the material from the bottom thereof, it has a strong tendency toward the action called "stacking" or "ridging," wherein the material compacts itself in such a way as to form an arch or bridge from side to side of the container which supports the superimposed material and allows the material below to be withdrawn without causing said superimposed material to follow it.

One of the objects of this invention, therefore, is to provide means whereby such stacking will be avoided and the uniform feeding of the material from the hopper will be insured.

Another object of this invention is to provide means for feeding the material in a disintegrated form directly from the hopper to the blast which delivers it for use, and to provide means for regulating the feed.

Further objects will appear from the detail description taken in connection with the accompanying drawing, in which:

Figure 1 represents a sectional view of a device embodying this invention;

Figure 2 is a section taken on the line 2—2, Figure 1; and

Figure 3 is a detail view of the regulating valve.

Referring now to the accompanying drawing, 1 designates a hopper which is to deliver the fuel to the feeding apparatus. This hopper is provided with a charging opening 2 and a discharging opening 3. Centrally located within the hopper 1 is a vertical tube 4 having a series of perforations 5 arranged helically, as shown in Figure 1. The tube 4 passes through the cover of the hopper 1 so as to communicate with the external atmosphere and permit a draught of air to be

drawn downwardly therethrough when the apparatus is working.

The hopper 1 rests upon and is supported by a cylinder 6 which has an opening corresponding to and registering with the opening 3 of the hopper 1. The cylinder 6 is supported at the rear end on the frame 7 and at the front end upon the housing 8 of a suction fan 9.

The fan 9 has a shaft 10 working in bearings in the housing 8 and extending rearwardly through the cylinder 6 and through a second cylinder 11 and is connected by means of the coupling 12 to a driving motor 13. The shaft 10 may be supported at intermediate points in bearings as 14 and 15.

Within the cylinder 6, is mounted a cylindrical regulating valve 16 having the shape shown in Figure 3. This valve has an opening 17 adapted to register with the opening 3 of the hopper 1 and has in addition, a series of perforations 18 adapted to partially close the lower end of the tube 4 when the valve 16 is in a position to partially close the opening 3. This valve is mounted for rotary adjustment within the cylinder 6 and is provided, for the purpose of such adjustment, with a handle 19 working in a slot 20 in the cylinder 6.

Within the valve 16 is a hollow cylindrical drum 21 provided with a series of circumferentially elongated perforations 22 over its entire surface. The drum 21 is mounted by means of spiders 23 and 24 upon the shaft 10, so as to rotate thereon. The rim 20 of the spider 24 is provided with an internal gear 25 adapted to mesh with a spur gear 26 supported by a bracket 27 upon the frame 7. The gear 26 meshes with and is driven by a pinion 28 carried by the shaft 10 and 95 driven by the motor 13. This arrangement is designed to give the drum 21 a slow rotation past the opening 3 of the hopper 1.

The cylinder 11 communicates with the outside atmosphere through a pipe 29 having a damper 30 adapted to regulate the supply of air.

In operation the motor 13, by means of the shaft 10, drives the exhaust fan 9, which draws a current of air down the pipe 29 105 through the cylinder 11 and through the hollow drum 21. The amount of air supplied may be regulated by the damper 30. Rotation of the shaft 10 also causes a slow rotation of the drum 21. The fuel in the 110

hopper 1 rests upon the drum 21 and when said drum is rotated, the fuel passes through the perforations 22 and enters the interior of the drum 21 in a disintegrated and finely divided state. Upon entering the interior of the drum, the fuel is caught by the current of air passing therethrough and the mixture of air and powdered fuel passes through the fan 9 and is delivered for use at 31.

The suction of air caused by the fan 9 produces a downward current of air through the pipe 4, which causes the fuel in the hopper to enter said pipe through the perforations 5, said fuel mixing with the air and passing to the interior of the drum 21 to be delivered by the fan 9 as before described. The continual entrance of fuel into the pipe 4 through the perforations 5 causes continual movement of the fuel in the hopper adjacent to said pipe and prevents, therefore, any packing of the fuel and any stacking or bridging action.

The amount of fuel delivered to the air current is regulated by means of the valve 16 by opening or partially closing the opening 3. It is thus seen that both the amount of fuel and the amount of air delivered to the mixture can be regulated as desired.

It will further be seen that this device feeds the fuel in a disintegrated form directly from the hopper, mixes it with the air and delivers the mixture for use. It will also be seen that stacking or bridging of the fuel in the hopper will effectively be prevented.

It is obvious that various changes may be made in the details of construction without departing from the spirit of this invention; it is, therefore, to be understood that this invention is not to be limited to the specific details as shown and described.

Having thus described the invention, what is claimed is:

1. Apparatus for feeding pulverized fuel, comprising, a hopper, a hollow, rotatable perforated drum at the outlet of said hopper and in contact with the fuel therein, adapted to feed the fuel therefrom, means for regulating the feed of the fuel, and means for causing a draught of air through said drum in order to mix with and deliver the fuel for use.

2. Apparatus for feeding pulverized fuel, comprising, a hopper, a hollow, rotatable perforated drum at the outlet of said hopper and in contact with the fuel therein, adapted to feed the fuel therefrom, means for regulating the feed of the fuel to said drum, and means for causing a draught of air through said drum in order to mix with and deliver the fuel for use.

3. Apparatus for feeding pulverized fuel, comprising, a hopper, a hollow, rotatable perforated drum at the outlet of said hopper

and in contact with the fuel therein, adapted to feed the fuel therefrom, a valve overlying said drum for regulating the feed of the fuel thereto, and means for causing a draught of air through said hollow drum adapted to mix with and deliver the fuel for use.

4. Apparatus for feeding pulverized fuel, comprising, a hopper, a hollow, rotatable perforated drum adapted to feed the fuel from said hopper, a valve embracing said drum adapted to regulate the feed of the fuel and means for causing a draught of air through said hollow drum adapted to mix with, and deliver the fuel for use.

5. Apparatus for feeding pulverized fuel, comprising, a hopper, an air duct in said hopper, a hollow, rotatable perforated drum adapted to feed the fuel from said hopper, a valve embracing said drum adapted to regulate the feed of the fuel and the passage of air through said duct, and means for causing a draught of air through said hollow drum adapted to mix with and deliver the fuel for use.

6. Apparatus for feeding pulverized fuel, comprising, a hopper, an air duct in said hopper, a hollow, rotatable perforated drum adapted to feed the fuel from said hopper, a valve embracing said drum adapted to regulate the feed of the fuel and having an opening adapted to regulate the passage of air through said duct, and means for causing a draught of air through said hollow drum adapted to mix with and deliver the fuel for use.

7. In an apparatus for feeding powdered fuel, a hopper adapted to contain the fuel and having an outlet at the bottom thereof through which the fuel is fed, and a perforated pipe in said hopper adapted to allow entrance of fuel to said pipe in order to prevent bridging of the fuel therein.

8. In an apparatus for feeding powdered fuel, a hopper adapted to contain the fuel and having an outlet at the bottom thereof through which the fuel is fed, and a perforated pipe in said hopper and means for passing a current of air through said pipe, adapted to cause entrance of fuel thereto in order to prevent bridging of fuel in said hopper.

9. An apparatus for feeding powdered fuel, comprising, a hopper adapted to contain said fuel, means in said hopper adapted to prevent stacking of the fuel, a hollow rotatable perforated drum adapted to feed the fuel from said hopper, a valve embracing said drum adapted to regulate the feed of the fuel, and means for delivering the fuel for use.

10. In an apparatus for feeding powdered fuel, a hopper adapted to contain the fuel, means for feeding the fuel from said hopper, and means in said hopper including a

perforated air pipe adapted to withdraw fuel from the body of the mass thereof to prevent stacking of the fuel.

11. In an apparatus for feeding powdered fuel, a fuel hopper having an outlet at the bottom thereof through which the fuel is fed, and suction means passing downwardly within said hopper and surrounded by the contents thereof, adapted to cause movement of the fuel adjacent thereto to prevent bridging within said hopper.

12. In an apparatus for feeding powdered fuel, a fuel hopper having an outlet at the bottom thereof through which the fuel is fed, and a perforated duct passing downwardly within said hopper and surrounded by the contents thereof, adapted to prevent bridging within said hopper.

13. In an apparatus for feeding powdered fuel, a fuel hopper having an outlet at the bottom thereof through which the fuel is fed, a perforated duct passing downwardly

within said hopper and surrounded by the contents thereof, and means for passing a current along said duct.

14. In an apparatus for feeding powdered fuel, a fuel hopper having an outlet at the bottom thereof through which the fuel is fed, a perforated duct passing downwardly within said hopper and surrounded by the contents thereof, and means for feeding the contents from said hopper.

15. In an apparatus for feeding powdered fuel, a fuel hopper having an outlet at the bottom thereof through which the fuel is fed, a perforated duct passing downwardly within said hopper and surrounded by the contents thereof and means for feeding the contents from said hopper, adapted to cause a current to pass through said duct.

In testimony whereof I affix my signature this 9th day of January, 1920.

ARTHUR C. GLASGOW.
